UNITED STATES PATENT OFFICE.

WILLIAM McNAMES, OF ABERDEEN, SOUTH DAKOTA.

WIRE-STRETCHER.

No. 813,574.

Specification of Letters Patent.

Patented Feb. 27, 1906.

Application filed May 5, 1905. Serial No. 258,973.

To all whom it may concern:

Be it known that I, WILLIAM McNAMES, a citizen of the United States, residing at Aberdeen, in the county of Brown and State of 5 South Dakota, have invented certain new and useful Improvements in Wire-Stretchers; and I do declare the following to be a full, clear, and exact description of the invention, such as will enable others skilled in the art to 10 to which it appertains to make and use the same, reference being had to the accompanying drawings, and to the figures of reference marked thereon, which form a part of this specification.

15 This invention relates to improvements in devices for stretching and repairing wire fences and wires used for fences, telegraphs, and other purposes, the object being to provide a wire-stretcher of simple and novel construction and by means of which wires and woven-wire fences may be stretched quickly and with comparatively little manual exertion. This and other objects I attain by the 20 novel construction and arrangement of parts 25 illustrated in the accompanying drawings, in which—

Figure 1 is a side elevation of my stretching device in position for stretching a woven-wire fence. Fig. 2 is a top view of the device 30 shown in the act of stretching a barbed wire preparatory to splicing it. Fig. 3 is a side elevation of one of the clamps by which the wire to be stretched is gripped.

Referring to the drawings by reference- 35 numerals, 4 is a yoke-shaped frame in which are journaled on two bolts or shafts 5 5^a two drums 6 6^a, each having a ratchet-wheel 7 or 7^a, operated in opposite directions by the dogs 8 8^a, pivotally carried by a bifurcated 40 hand-lever 9, pivoted at 10 to both sides of the frame.

11 represents pawls locking the ratchet-wheels while the dogs 8 take new hold.

From the dogs 8 extend upward through 45 apertures 12 in the shoulders of the lever 9 rods 13, serving as guides for helical springs 14, by which the dogs are held in engagement with the ratchet-wheels.

Upon each spool or drum is wound a cable 50 or rope 15, carrying in its free end a snap-hook 16, adapted for ready attachment in various manners as the case may require. Thus to the left in Fig. 1 is shown how the rope is taken around a fence-post or other post 17 55 and the snap 16 engaged with the rope itself, while to the right the snap engages in the

crutch of a two-armed rope 18, having at its ends cold-shuts 19, held apart by a cross-bar 20, having its reduced ends inserted in the cold-shuts or other rings, which in Fig. 1 carry 60 clamping devices 21, of which only two are shown in Fig. 1; but there may be several of them attached to the snap-hook by arms like 18^a and rings or cold-shuts 19^a, so that a woven-wire fence, as indicated at 22 23, may 65 have its longitudinal wires 23 clamped between the corrugated shoe 24 and the corrugated cam 25 of any desired number of clamps. The clamp 21 consists of a shoe or plate 24, having holes in one end for the ring 70 19 and in the other end for the hook 29, which may help take hold of the meshes or cross-bars of a woven fence, as indicated in Fig. 1.

25 is a bifurcated or double cam straddling the central upright 27, to which it is pivoted at 26, while its upper end forms a short handle 28.

30 represents guarding-lips on the shoe to prevent too easy or accidental disengagement of the wire from the clamp.

In Fig. 3 is shown how a single wire 31 may be stretched by such a clamp, in which case the snap-hook may simply engage in the ring or link 19, the same as in Fig. 2, where the 85 stretcher is shown as interposed between the ends of a broken wire 32, which is to be pulled together and spliced or mended. In this case the clamps are separated and attached one to each rope 15.

90 In the operation of the device when the lever 9 is vibrated on its pivot 10 the dogs 8 rotate both of the drums 6, thus pulling in the two ropes 15, thereby doubling the speed of the work, while losing none of the pressure or 95 force such a lever will furnish.

It is evident also that the clamp is capable of holding one wire at each side of the post 27, so that two parallel wires, whether in a woven fence or separate, may be stretched 100 by one clamp in one operation, and by using several clamps, as in Fig. 1, a whole fence may be stretched in one operation.

Having thus described my invention, I claim as new and desire to secure by Letters 105 Patent—

1. A wire-stretcher comprising an elongated open frame, an operating-lever pivoted at the middle thereof, two spring-pressed dogs carried by the lever, two rope-drums 110 mounted in the frame, one near each side of the lever, ratchet-wheels on the drums oper-

ated by the dogs, stopping-pawl pivoted to the frame and engaging the ratchet-wheels, two ropes, one wound on each drum and having at their free ends means for attaching them to objects.

2. A wire-stretcher comprising an elongated open frame, an operating-lever pivoted at the middle thereof, two spring-pressed dogs carried by the lever, two rope-drums mounted in the frame, one near each side of the lever, ratchet-wheels on the drums operated by the dogs, stopping-pawl pivoted to the frame and engaging the ratchet-wheels, two ropes, one wound on each drum, and snap-hooks secured to the free ends of one or both of the ropes.

3. A wire-stretcher comprising an elongated open frame, an operating-lever pivoted at the middle thereof, two spring-pressed dogs carried by the lever, two rope-drums mounted in the frame, one near each side of the lever, ratchet-wheels on the drums operated by the dogs, stopping-pawl pivoted to the frame and engaging the ratchet-wheels, two ropes, one wound on each drum, a plurality of arms, 18 18^a, extending from the outer end of one of the ropes, wire-clamping devices carried by each of said arms, and means for holding the arms spread.

4. A wire-stretcher comprising an elongated open frame, an operating-lever pivoted at the middle thereof, two spring-pressed dogs carried by the lever, two rope-drums mounted in the frame, one near each side of the lever, ratchet-wheels on the drums operated by the dogs, stopping-pawl pivoted to the frame and engaging the ratchet-wheels, two ropes, one wound on each drum, a plurality of arms, 18 18^a, extending from the outer end of one of the ropes, wire-clamping devices carried by each of said arms, and means for holding the arms spread.

40

5. A wire-stretcher comprising an elongated open frame, an operating-lever pivoted at the middle thereof, two spring-pressed dogs carried by the lever, two rope-drums mounted in the frame, one near each side of the lever, ratchet-wheels on the drums operated by the dogs, stopping-pawl pivoted to the frame and engaging the ratchet-wheels, two ropes, one wound on each drum, a plurality of arms, 18 18^a, extending from the outer end of one of the ropes, wire-clamping devices carried by each of said arms, and means for holding the arms spread, and snap-hooks at the ends of the two ropes, substantially as and for the purposes set forth.

45 In testimony whereof I affix my signature in presence of two witnesses.

WILLIAM McNAMES.
